NONREFILLABLE BOTTLE CLOSURE

Harry Pollack and Louis Davang, Brooklyn, N. Y.

Application March 16, 1937, Serial No. 131,139

10 Claims. (Cl. 215—21)

This invention relates to a non-refillable bottle device of the type adapted to serve as a closure for bottles, permitting the outflow of the fluid contents and preventing the refilling of the bottle 5 with a substituted fluid.

Cognizance is taken of the fact that many attempts have been made to provide bottle closures of this type, but it is common knowledge that many of such devices can be manipulated in 10 such manner as to permit the introduction of a substituted fluid into the bottle without affecting the subsequent operation thereof, or without showing visible signs that such bottles have been tampered with. It is within the contemplation 15 of our invention to overcome such shortcomings by providing a closure that will at all times permit the original liquid contents to be poured out of the bottle, and eliminate the possibility of introducing substituted contents without visibly 20 and otherwise noticeably giving evidence that the closure has been tampered with.

Another object of this invention is to permit, in a device of this nature, the original fluid contents to be poured out readily and smoothly at 25 all times.

Still another object is to provide a construction of simple and inexpensive design that will accomplish the aforementioned purposes.

Other objects, features and advantages will 30 appear from the drawing and the description hereinafter given.

Referring to the drawing,

Figure 1 is a fragmentary vertical section of 35 a bottle showing our invention in operative position with the outlet passageway closed.

Figure 2 is a plan view of Figure 1.

Figure 3 is a transverse section of Figure 1 taken along line 3—3.

Figure 4 is a fragmentary vertical section of 40 Figure 3 taken along line 4—4.

Figure 5 is a bottom view of the device constituting our invention, and

Figure 6 is a fragmentary section taken along the longitudinal axis of a bottle containing our 45 invention, the parts being shown in position to permit the outflow of the fluid contents.

In the drawing, the neck of the bottle 10 suitably accommodates the substantially hollow cylindrical plug or body portion 11 of the device,—the upper periphery of the bottle, in the preferred arrangement, containing a recess 12 for operatively receiving the flange 13 of said plug. An outer shell or lining 14 made preferably of cork is interposed between the plug 11 and the 55 bottle 10, so as to provide an air-tight and

resilient seal. It will be noted that the said lining 14 extends upwardly to the underside of the flange 13, so that no access thereto can be had from the outer periphery of the bottle.

The said plug 11 contains therein the spout 15 communicating through the passageways 16 and 17 with the annular inner chamber 18. The passageway 19 in said plug is positioned preferably diametrically opposite to the passageway 17, and communicates through the outer annular 10 chamber 26 with the longitudinal chamber or channel 20 which extends downwardly towards the base of said plug and terminates adjacent the space 21. The plug 11 also contains a longitudinal central member 22 in spaced relation to 15 the lateral wall 23 of the plug.

A substantially cylindrical hollow valve member 24 is slidably positioned over the said central member 22, the lateral wall 25 thereof being movable within the said annular outer chamber 26 20 in the plug 11. It will be observed that the valve 24 is provided with extensions 24a and 24b which fit into appropriate recesses in the plug 11 to permit it to slidably move therein (see Figure 3). The upper portion of said valve 24 is cut away to 25 form an opening 27 as shown on the drawing, the lower wall 28 thereof being preferably downwardly bevelled. The said slideable valve 24 also contains in the lateral wall thereof a recessed duct 29 communicating, when the valve is in its closed 30 or lowermost position, with the interior of the bottle through the channel 30 in the said plug. The channel 31 at the upper portion of the plug 35 communicates with the outer annular chamber 26 and the atmosphere through the four small holes 32. The relative positions and dimensions of the channel 31 and recessed duct 29 are such that when the valve is in its open or uppermost 40 position, the said recessed duct will be in communication with the channels 30 and 31. Note 40 should also be taken of the fact that the upper wall 33 of said recessed portion 29 is downwardly bevelled as shown.

In the assembling of this device, the valve 24 is slidably positioned over the said central portion 22 as indicated, and thereafter the substantially U-shaped retaining wire 34 is placed in position with the cross bar 35 underlying the valve 24 and the plug 11. With the parts so assembled and with the fingers 36 and 37 positioned within the holes 38 and 39 in the plug, the device is inserted 50 into the bottle until the said fingers 36 and 37 reach the level of recesses 40 and 41 within the neck of the bottle. Inasmuch as the upwardly extending arms 42 and 43 of the retaining wire 55

- 34 are resilient in nature, the upper outwardly flared portions 42a and 43a of said arms will spring outwardly into said recesses 40 and 41, thereby holding the assembled device in place.
- 5 Note should be taken that the said plug contains recesses 44 and 45 in the lateral side thereof to accommodate the said arms 42 and 43 of the retaining wire 34. It is obvious that it is now permanently affixed in place, and cannot be removed
- 10 except by breaking the bottle.

When the device is in the position shown in Figure 1, it will be noted that the valve thereof is closed, there being no direct communication between the interior of the bottle and the spout

15 15. However, when the bottle is inverted, as shown in Figure 6, the valve 41 will slide downwardly until it comes into abutment with the upper wall 26a of chamber 26. In this position, there is direct communication between the interior of the bottle through the space 21, the port 21a, the chambers 20 and 26, the port or passageway 19, around the inner annular chamber 18, and out through the passageways 17, 16 and spout 15. When the parts are in this position, 20 the liquid contents can freely flow out of the bottle as shown by the arrows. To facilitate such a flow, the holes 32, the passageway 31, port 31a, and passageways 29 and 30 are provided whereby air is drawn therethrough into the bottle to prevent the formation of a vacuum and provide sufficient air pressure for the purpose. (See Figure 6.)

When the bottle is in its inverted operative position, it is apparent that no instrument or wire 35 can be inserted within the structure so as to operatively hold the valve 22 in its open position, whereby a substituted fluid can be introduced by suction. Such an insertion or manipulation is rendered practically impossible due to the fact 40 that such instrument would have to follow a circuitous path extending through the passageways 16, 17, the annular chamber 18, the passageway 19, the chambers 26 and 20, and then around to the surface 28 of valve 24. It is thus obvious that 45 such a path would constitute an unsurmountable barrier to almost any instrument whatsoever. Neither would it be possible to engage the surface 28 of the valve 24 to frictionally hold it in its open position due to the fact that such surface 50 is bevelled as indicated.

Should an attempt be made to hold the valve 24 in its open position by inserting an instrument through the channel 31, such a procedure would be wholly impracticable, for several reasons. In 55 the first place, the openings 32 can be made sufficiently small to prevent an instrument from being operatively inserted therethrough. In the second place, should an instrument be manipulated through said holes, it would have to pass 60 through the inclined passageways connecting said holes 32 and channel 31, and then through a right angle turn at 48. At this point the instrument will engage an inclined surface 33, preventing a frictional engagement for such purpose. 65 If, for the purpose of entering the channel 31, the four holes 32 are enlarged into one large one by a drill, there will be visible evidence that the device has been tampered with. The four holes, when intact, thus constitute a visible symbol to 70 show that the device has not been tampered with, and that the contents within the bottle are genuine.

It thus appears that the structure constituting our invention is a practical closure for a bottle, and provided with cooperative elements adapted

to prevent a substitution of the original fluid contents of the bottle, or to give visible evidence that the device has been tampered with. The entire structure consists essentially of two major parts that can be readily fabricated from molds, the two additional parts, namely the retaining wire 34 and the lining 14 being of simple and inexpensive construction. It is also apparent that the assembly can be readily effected without the employment of any specially skilled help.

It is of course understood that the various embodiments above described and shown in the drawing are illustrative of our invention and not employed by way of limitation, inasmuch as numerous changes and modifications may be made 15 within the scope of the appended claims without departing from the spirit of this invention.

What we claim is:

1. In an unrefillable bottle closure, a substantially hollow plug adapted to be inserted within the neck of a bottle, a central member longitudinally disposed within the plug and in spaced relation to the lateral wall thereof whereby an annular chamber is formed therebetween, the central member being shorter than the plug whereby 25 a space is formed in the region of the base of the plug, said plug containing a longitudinal chamber communicating with said annular chamber and extending to the region of said space, a hollow valve member having its lateral wall in slidable 30 engagement with said central member and movable within said annular chamber and space, means to limit the movement of said valve member from its closed or most remote position from the mouth of the bottle to its open or nearest 35 position with respect to said mouth, the said wall of the valve member being interposed between said longitudinal chamber and said space when the valve is in its said closed position, said longitudinal chamber and said space being in communication when the valve member is in its said open position, the said wall of the valve member having an opening therein communicating with said annular chamber, and a spout at the outlet 40 end of the plug communicating with said annular chamber.

2. In an unrefillable bottle closure, a substantially hollow plug adapted to be inserted within the neck of a bottle and containing two substantially concentric annular chambers therein, 50 a spout in the outlet end of the plug, two independent passageways communicating with the inner of said annular chambers, one of said passageways leading to said spout and the other to the outer of said annular chambers, a longitudinal chamber communicating with the outer of said annular chambers, a port communicating with said longitudinal chamber and the interior of said bottle, and valve means operatively associated with said port.

3. In an unrefillable bottle closure, a substantially hollow plug adapted to be inserted within the neck of a bottle and containing an inner chamber, an outer chamber spaced therefrom, a spout in the outlet end of the plug, two independent passageways communicating with the said inner chamber, one of said passageways leading to said spout and the other to the said outer chamber, a longitudinal chamber communicating with the outer of said annular chambers, a port communicating with said longitudinal chamber and the interior of said bottle, valve means operatively associated with said port, and locking means for securing the plug to the neck of the bottle.

4. In an unrefillable bottle closure, a substantially hollow plug adapted to be inserted within the neck of a bottle and containing an inner annular chamber, a spout in the outlet end of the plug, a longitudinal channel, a port communicating with said longitudinal channel and the interior of said bottle, two independent diametrically opposite passageways, one of said passageways leading to said spout and the other communicating with said longitudinal channel, and valve means operatively associated with said port.

5. In an unrefillable bottle structure, a bottle neck having two recesses in the inner wall thereof, a valve-containing body portion adapted to be inserted within the said neck, and a substantially U-shaped retaining wire comprising a cross bar in underlying supporting engagement with the base of said body portion, and two upwardly extending resilient arms containing upper outwardly flared portions extending into said recesses, the upper terminal portions of said arms containing inwardly extending fingers, the said body portion containing holes therein adjacent the said recesses in said neck and into which said fingers extend.

6. In an unrefillable bottle closure, a substantially hollow plug adapted to be inserted within the neck of a bottle, a central member longitudinally disposed within the plug and in spaced relation to the lateral wall thereof whereby an annular chamber is formed therebetween, said lateral wall containing two independent channels communicating with said chamber, one of said channels leading to the atmosphere through the mouth end of said plug, and the other to the interior of the bottle through the base of said plug, a hollow valve member having its lateral wall in slidable engagement with said central member and movable within said annular chamber, means to limit the movement of said valve member from its most remote position from the mouth of the bottle to its nearest position with respect to said mouth, said valve member containing in its outer lateral wall a longitudinal recessed portion adapted to communicate with both of said channels only when the valve member is in its said position nearest the mouth of the bottle, a spout in communication with said annular chamber, said chamber being in communication with the interior of the bottle, and valve means operatively positioned between the interior of the bottle and said annular chamber.

7. In an unrefillable bottle closure, a substantially hollow plug adapted to be inserted within the neck of a bottle, a central member longitudinally disposed within the plug and in spaced relation to the lateral wall thereof whereby an annular chamber is formed therebetween, the central member being shorter than the plug whereby a space is formed in the region of the base of the plug, said plug containing a longitudinal chamber communicating with said annular chamber and extending to the region of said

space, a hollow valve member having its lateral wall in slidable engagement with said central member and movable within said annular chamber and space, a substantially U-shaped retaining wire comprising a cross bar in underlying supporting engagement with the base of said plug and said valve member to hold the latter in its closed or most remote position from the mouth of the bottle, said retaining wire containing two upwardly extending resilient arms in locking engagement with the neck of the bottle and the said plug, the said annular chamber terminating near the mouth end of the bottle in a wall adapted to engage said valve member and hold it in its open or nearest position with respect to said mouth, the said wall of the valve member being interposed between said longitudinal chamber and said space when the valve is in its said closed position, said longitudinal chamber and said space being in communication when the valve member is in its said open position, the said wall of the valve member having an opening therein communicating with said annular chamber, and a spout at the outlet end of the plug communicating with said annular chamber.

8. In an unrefillable bottle closure, a valve-containing body portion adapted to be inserted within the neck of the bottle and containing a chamber therein, a channel communicating with the atmosphere through the outer end of said body portion, the inner end of said channel containing an angular bend terminating in a port, and a slide valve in said chamber operatively associated with said port, said valve containing a recessed duct communicating with said port and the interior of the bottle, the upper wall of said duct being inclined downwardly.

9. In an unrefillable bottle closure, a valve-containing body portion adapted to be inserted within the neck of the bottle and containing a chamber communicating with the interior of the bottle, a channel in said body portion terminating at its inner end in a port communicating with said chamber, a plurality of passageways inclined with respect to said channel and communicating between the channel and the outer exposed end of said body portion, and valve means operatively associated with said port.

10. In an unrefillable bottle closure, a valve-containing body portion adapted to be inserted within the neck of the bottle and containing a chamber communicating with the interior of the bottle, a laterally enclosed channel entirely within said body portion terminating at its inner end in a port communicating with said chamber, the said body portion containing at its outer end and in spaced relation to the edge thereof a cluster of relatively small adjacent and laterally enclosed holes leading directly into said channel, and valve means operatively associated with said port.
